UNITED STATES PATENT OFFICE.

THOMAS I. DUFFY, OF CHICAGO, ILLINOIS.

AUTOMATIC GATE.

SPECIFICATION forming part of Letters Patent No. 756,781, dated April 5, 1904.

Application filed December 30, 1901. Serial No. 87,655. (No model.)

To all whom it may concern:

Be it known that I, THOMAS I. DUFFY, a citizen of the United States, and a resident of Chicago, in the county of Cook and State of Illinois, have invented certain new and useful Improvements in Collapsible Gates; and I do hereby declare that the following is a full, clear, and exact description thereof, reference being had to the accompanying drawings, and to the letters of reference marked thereon, which form a part of this specification.

This invention relates to improvements in automatic gates, and more particularly to that class of automatic gates designed for use on car-platforms or the like. Heretofore with inventions of this class it has been common to provide a gate hinged on one side at the end of the car and adapted to swing inwardly to permit the passengers to board or leave the car. This type of gate has been objectionable owing to the amount of space required to permit the same to swing inwardly sufficiently to permit egress from the car and also for the reason that the same has been inconvenient to the operator when the car-platforms are crowded. Another type of gate is a laterally-collapsible gate which may be telescoped or folded against the side of the car when not in use, occupying little space. Gates of this description when in use owing to their peculiar construction do not afford sufficient resistance to protect the passenger from falling from the car.

The object of my invention is to provide a folding gate of great rigidity and strength when in use and which is adapted to fold into a very small compass at the end of the car.

The invention embraces means whereby an operator or guard standing partly on two cars may operate both gates at one and the same time.

The invention consists in the matters hereinafter described, and more fully pointed out and defined in the appended claims.

In the drawings, Figure 1 is a fragmentary side elevation of a car provided with a gate embodying my invention. Fig. 2 is a horizontal section of a car, showing the platform and the gates in plan view. Fig. 3 is an enlarged side elevation of the gate, showing the

same in its closed position. Fig. 4 is a similar view showing the gate in its open position. Fig. 5 is a vertical section of one of the bearings upon which the gate moves.

In said drawings, A indicates a passenger or street car of any desired construction provided at its end with platforms a. Said platforms may be vestibuled in a familiar manner or may be provided with the uprights a' a'', forming a partial end wall at the extremity of the platform. The gate is pivoted on the upright or standard a' and consists of the upper and lower transverse members B and B', having pivotally secured thereon vertical slats or cross-pieces b. Said slats, as shown, engage at their ends on the outer side of one of the transverse members and the inner side of the other, and between the slats b said transverse members are bent or offset, as indicated in Figs. 2, 3, and 4, to permit the said slats b to pass by and to lie flat against each other, as indicated in Fig. 4, when the gate is in its opened condition. Means are provided for opening and closing said gate, as follows: On the ends of the vestibule or, as shown, secured on the upright a' are the rigidly-secured pivot-arms C C', provided with horizontal laterally-projecting arms or pivots c c', on which are secured the respective gate members B and B' by means of the bell-cranks d' d'', one end of each of which is secured to the respective members B and B' and the other ends of which project beyond the pivot, as shown in Fig. 3, and are pivotally connected with the connecting-rod C' at the opposite ends thereof. D indicates a shaft journaled transversely of the platform on said partial end wall or on the members a' a'' and provided at opposite ends with cranks d d', of which that indicated by d is relatively short and engages the connecting-rod C', as indicated in Figs. 3 and 4. The other of said cranks, or d', is longer and includes a handle for manual engagement. Pivoted on the crank d' is a lever d'' in position to be manually engaged when the handle is grasped by the operator and provided at its inner end with a dog adapted to engage in sockets in the bearings d'' adjacent to said crank and at its outer end with a spring d'', engaging on said handle.

adapted to throw the dog into locking position. The sockets in said bearings are so located that the dog engages in one of the same when the gate is in its closed position, as indicated in Fig. 3, and in another when the gate is in its open position, as shown in Fig. 4. Means are also provided for securing the free ends of the transverse members B B' on the car ends when the gate is in its closed position. For this purpose socket-pieces E are rigidly secured to the car end in position to engage the free end of said members. Said socket-pieces open on their upper side to permit said members to fall readily to position.

15 Obviously many details of construction may be varied to provide precision of alinement when dropping the gate into its closed position, and for this purpose, if preferred, each of the bell-cranks may be provided with an elongated sleeve to engage the pivot-pin c. Obviously the gate may be opened on either side the opening, as preferred, and many details of construction may be varied without departing from the principle of my invention.

25 I claim as my invention—

1. A collapsible gate comprising upper and lower transverse members adapted to extend across the opening to be closed and having a series of equidistant bends, a series of connecting members pivotally secured to said transverse members between said bends, connected bell-cranks at the inner ends of said transverse members and a lever engaging the connection between said bell-cranks.
- 35 2. In a gate, an upper and a lower transverse bar having pivoted thereon vertical slats spaced an equal distance apart said transverse bars being bent and connected on opposite sides of said slats whereby when the gate is elevated said vertical slats and transverse bars are adapted to collapse laterally and to expand vertically upward.
- 40 3. In a device of the class described the combination with an upright having rigidly secured thereon outwardly-extending parallel arms, of bell-crank levers pivoted on said arms, undulated transverse members secured on said bell-cranks, a plurality of slats pivoted on said members between the undulations thereof, a connecting-rod pivotally engaging each bell-crank and a crank engaging said connecting-rod and acting to collapse the gate laterally

and move said transverse members to a vertical position.

4. In a railway-gate the combination with a support of parallel pivot-arms rigidly secured thereon a bell-crank on each pivot, a transverse bar secured to each bell-crank, vertical slats connected at their opposite ends on opposite sides of said transverse bars offsets in said transverse bars between adjacent slats to permit said slats to lie together when the gate is open and spring-actuated means for locking the gate in its closed position and in its open position.

5. In a device of the class described the combination in a vertically-opening and laterally-collapsible gate, of means for actuating the gate comprising a shaft, a crank thereon adapted to engage a vertically-movable member, a bell-crank pivotally secured on each end of said vertically-movable member and rigidly secured upon the gate, a crank adapted to be manually engaged in operating the gate and a spring-actuated dog acting to hold the gate from movement when in its open or closed position.

6. In a device of the class described the combination with a permanent upright, of parallel pivot-arms rigidly secured thereon, a bell-crank pivotally secured on each of said arms, a vertically-movable member pivotally connected with said bell-cranks, an undulated transverse member rigidly secured on each of said bell-cranks and a plurality of slats pivotally connected with said undulated members each lying out of the plane of the other.

7. A collapsible gate comprising transverse members provided with a plurality of offsets, a plurality of vertical slats pivotally secured thereto between said offsets, means for operating the gate, said gate lying in the plane of the opening to be closed when in its closed position and lying in a plane at approximately right angles thereto when in its open position with the faces of said slats in contact with the faces of adjacent slats.

In witness whereof I have hereunto subscribed my name in the presence of two subscribing witnesses.

THOMAS I. DUFFY.
